UNITED STATES PATENT OFFICE.

CARL J. BAER, OF ST. LOUIS, MISSOURI.

DREDGING SYSTEM.

1,399,286.

Specification of Letters Patent.

Patented Dec. 6, 1921.

Application filed July 28, 1920. Serial No. 399,544.

To all whom it may concern:

Be it known that I, CARL J. BAER, a citizen of the United States, residing at St. Louis, in the State of Missouri, have invented certain new and useful Improvements in Dredging Systems, of which the following is a specification.

My invention relates primarily to means for and method of dredging rivers and, more particularly, to the provision of means and methods whereby navigable channels may be cut in beds of rivers of shallow waters, although, as hereinafter pointed out, the invention may be effectively practised in the deeper waters. The invention also contemplates the removal of obstructive sand bars and alluvial deposits, whereby, in certain cases, a channel is restored.

The present method of forming navigable channels is by the utilization of the well known steam dredges, usually carrying dredging buckets, which cut out the channel and deposit the sand and silt upon scows or barges for removal. This system is, in some localities, prohibitively expensive and is always a long and tedious undertaking.

My method contemplates the utilization of means confining the running water to the proper limits and direction, thereby increasing the speed of said water and forcing it to take the desired path and cut the proper channel, or to remove the bar of sand or alluvial deposit.

Such a method has been attempted in the past, but, due to the omission of certain steps of the method, and because of the non-recognizance of well-known engineering laws, such attempts have heretofore been abortive. My invention therefore consists generally in the method and means whereby the above named objects are obtainable, together with others which will hereinafter appear.

The nature of the system devised by me for accomplishing the proposed result, makes it appropriate that, before entering into the details thereof, I should briefly outline the technical considerations upon which it is based.

A serious difficulty which, in many parts of the world, constitutes a veritable bar to

river navigation on a very large scale, consists in the fact that, while the main river waterways are commercially navigable along a portion of their length, the difficulty of navigation increases in approaching the source. Moreover the very large inland waterways, such as the Mississippi, are fed by numerous tributaries such as the Arkansas, and such tributaries, especially in flat countries, are usually a very wide body of water of a depth not permitting commercial navigation.

A further impedance to river navigation consists in the tendency of many rivers to form bars of sand and other alluvial deposits, not only at their mouths but also at the point of confluence with other rivers. The cause in both cases is the contrary action and partial equilibrium of two opposing currents—as, for example, that of the river against that of the tide in the one case, and those of two confluent streams in the other case. Such bars effectively block any channels which may have previously been formed, and the removal of these bars constitutes a restoration of a channel.

Up to the present time, as before stated, the most efficacious means which have been employed for the purpose of counteracting to some degree the formation of such bars, consists in the utilization of powerful dredges, the building of permanent wing dams, jetties, etc. Some of the attendant disadvantages of the dredging system have been enumerated, and a long and detailed study of river currents, involving years of experimentation, has led me to believe that the dredging system is not the most efficacious for removing bars and cutting channels. I have therefore sought to devise a system which, by availing itself of the force of the current of the stream, should provide a permanent remedy, and one which involves a comparatively small original outlay, together with a minimum of subsequent work. This system as will hereinafter appear, consists not only in initially cutting channels in large inland water ways above the present point of navigation, but in forming such channels in tributaries; also in removing

bars of sand or alluvial deposits which have partially or wholly blocked the previously formed channels, the necessary power for carrying out the major portion of the work being in all cases furnished by the force of the water of the stream, confined within certain predetermined limits.

The accompanying drawings which form a part of this specification, illustrate my method and a novel apparatus capable of practising it.

This application is a continuation, in part, of my application Serial No. 328,787, "Dredging systems," filed October 6, 1919.

15 In the drawings:—

Figure 1 is a detailed plan view, showing a plurality of dam units in operative position.

Fig. 2 is a side elevation of one of the dam units.

Fig. 3 is a cross-section taken on line 3—3 of Fig. 2.

Fig. 4 is a cross-section taken on line 4—4 of Fig. 2.

25 Fig. 5 is a plan top view of the unit.

Fig. 6 is an enlarged section on line 6—6 of Fig. 5.

Fig. 7 is a diagrammatic view showing the dam unit with its front end elevated and its 30 rear end submerged.

Fig. 8 is a detail plan view of one of the sealing plates.

Fig. 9 is a diagrammatic view of the adjacent ends of two units showing method of 35 contact of the sealing plates.

Fig. 10 is a section taken on line 8—8 of Fig. 2.

Fig. 11 is a detail of the chain links.

Fig. 12 is a fragmentary perspective view 40 showing the partitions, sealing plates, and guides therefor.

The dam unit.

In order to practice my method, I have 45 devised a dam unit which is possessed of several novel characteristics. It is equipped with a tractive device which, by means of a motor, is capable of propelling the unit through the water, or on the land. The 50 tractive device extends downwardly below the hull of the unit, and, upon engagement with the bottom or bed of the river or other body of water, is capable of moving the unit along the bottom or bed.

55 The unit is provided with a plurality of water tight compartments, and with means whereby said compartments may be individually flooded and emptied. Either end of the unit may be in its normal position on 60 the water, while the other end is submerged.

In the drawings, the unit, as a whole, is indicated by the letter A, and is preferably of the general configuration shown in the drawings. It is preferably formed of metal 65 plates, so that it may withstand the pressures

and other usages to which it is subjected in operation, but the particular material is unimportant, so long as it is of sufficient strength and buoyancy.

As shown in the drawings the unit is provided with side plates B, a deck C and a hull D. The prow E is here shown as convexed, and the stern F as concaved, for a purpose to be hereinafter specified.

The unit is here shown as provided with a tractive device somewhat similar to a caterpillar tractor. This device consists of an endless chain 2, provided with a plurality of paddle or "stepper" members 3, the chain having a longitudinal path of travel from approximately end to end of the unit, and extending vertically below the hull and also above the water line, as shown in Fig. 2. The chain is made up of links 4, to which the paddles or steppers 3 are suitably secured. Guide wheels 5, 5 are secured to each end of the unit, and guide rollers 6, 6 are similarly secured near the bottom of the plates B. One tractive element as herein described, is provided for each side of the unit.

A motor G is provided for each tractive device, said motor being of any preferred type, and preferably mounted upon the deck structure. The motor shaft 7 is here shown as extending longitudinally of the deck, and carries a worm 8, adapted for co-operation with a worm gear 9. The worm gear 9 is carried by a shaft 10 supported at one end and having bearing in a bracket 11, the other end of said shaft extending through the side B of the unit, and carrying pinions 12, 12 provided with teeth adapted to engage the links 4 of the chain 2. It is obvious from the foregoing that, when the motor is turning the shaft 7, and the parts in the position shown in Fig. 2, the tractive element is being forced around the rollers 5 and 6. In order to properly support and better guide the tractive element, a runway B' is provided at either side of the unit, as clearly shown in Fig. 3, by so forming the sides that they project and occupy the space between the upper and lower portions of the element. 1 In actual practice, anti-friction rollers are placed in the runways B'.

A clutch member 13, operated by a hand lever 14, is adapted to couple and uncouple the shaft 7 to the shaft 7' which carries the flywheel 15.

The unit is here shown as interiorly provided, on each side, with three compartments, H, I and J. The compartments H and J are of course watertight and are provided with gates 16 operable to open and close ports 17 which permit ingress of water, when it is desired to partially submerge the units. The compartments H and J are separated from the compartment I, which

contains the gears 9, shafts 10 etc., by partitions 18, 19, shown in dotted lines in Fig. 2.

The gates 16 are here shown as vertically 5 slideable. As indicated in Fig. 4 each gate is vertically slideable in a track or guideway 20, and is provided with a laterally extending lug 21 which incloses an interiorly screw-threaded collar 22. Extending through a bearing bracket 23, is a rod 24, the lower 10 end of said rod being screw-threaded and extending through the collar 22, rigidly secured to the lug 21. To the upper end of the rod 24 is secured a beveled pinion 25, in mesh with a similar pinion 26 carried by a shaft 27 which has bearing in the plate B. The other end of said shaft is supported in a depending bracket 28, and carries a pinion 29 which is in mesh with a pinion 30, carried by a stub shaft 31. As shown, the shaft 31 15 extends through the deck C, and carries a hand wheel 32 whereby the shaft may be rotated.

It is obvious from the foregoing that rotation of the hand wheel 32 will cause a vertical 20 movement of the gates 16, to open or close the ports 17, in the compartments H and J. When it is desired to allow the unit to rest upon the bottom, the ports 17 are 25 opened and the compartments H and J, either or both, are flooded. It now becomes necessary to restore the buoyancy of the unit by emptying the compartments H and J—one or both.

Mounted above the compartment J, on each side, is a pump K. As shown in Fig. 6, one of the pumps K is provided with a pipe 33, connected to two pipes 33' and 33'', the latter passing through the deck and terminating in screens 34, adjacent the 30 floor of the compartment. This pump is adapted to empty the two front compartments. The other pump K is provided with a pipe 33^a, extending rearwardly and into one of the compartments in the 35 rear. A branch pipe 33^b connects with the pipe 33^a, and extends into the opposite rear compartment. This pump K is therefore operable to empty the two rear compartments.

50 The pump K is shown as power operated. It is mounted upon a shaft in alinement with the shaft of the motor G, and a clutch 36, operated by a hand lever 37 is adapted to couple and uncouple the pump K to said shaft, as will be understood.

The sealing plates.

55 The beds of rivers are ordinarily uneven. As will hereinafter appear a step in my method necessitates that the units be sunk upon the bed of the river, and, if the bed under the unit is not level, the water will pass below the unit. To prevent this objectionable feature, and to provide additional mooring effect while the dam is being

formed, as will hereinafter be more fully explained, I provide a plurality of sealing plates M. These plates are here shown as extending longitudinally of the unit, and adapted for vertical movement with respect 70 thereto.

The plates M are formed of any suitable material, but preferably of sheet metal. A plurality of them are arranged in alinement, and adapted for interfitting and dovetail 75 engagement, as clearly shown in Fig. 8. Each plate is provided on its side face with a worm rack 40. Adjacent this rack and in operative engagement therewith is a worm shaft 41 having a bearing 42 in the bottom 80 of the unit, and terminating above the deck of the unit in an operating wheel 43. By turning the wheel 43 the plates M may be raised or lowered as desired. Each of the plates are alike, and the operating mechanism just described is applicable to all of them. Each plate may be independently 85 operated.

The operating wheel 43 is here shown as a hand wheel. It will be obvious, however, 90 that the shaft 41 might readily be connected up to the shaft 7, by means of worm gears or otherwise, so that the plates could be moved by power from the motor G.

As shown in the drawings the end plates 95 of each unit project beyond the body of the unit, for interfitting engagement with the projecting plate of the adjacent unit. From an inspection of Fig. 1 it will be observed that, when the units are arranged in alinement 100 the rear plate M of one unit receives the sharp edge of the front plate of the adjacent unit, thereby preserving the water seal. When the units are disposed at an angle, as also shown in Fig. 1, the plates of 105 the adjacent units overlap.

I utilize a plurality of plates M, for two reasons: first, because of the possibility of a stone or rock being in the path of the descending plates, in which event the plate or 110 plates which would contact the rock are left in elevated position; secondly, because it is easier to manipulate a plurality of relatively light plates than one heavy plate.

The plates M are housed entirely below 115 the deck of the limit and are mounted between two parallel partitions M', which extend longitudinally and vertically of the unit and are secured to the deck, hull and ends of the unit by watertight joints, and 120 preferably riveted in position as shown in Figs. 3, 4, 5 and 6. It will be noted that the partitions M' form the inside wall of the compartments H, I and J.

Extending vertically between the partitions M', and located adjacent the meeting edges of the contacting plates M, are two channel iron members M². Said members M² are bolted or riveted to the partitions M', as clearly indicated in Figs. 10 and 12. As 130

shown in Figs. 8 and 12, the plates M are provided with cut-away portions forming shoulders M³, adapted to contact a block M⁴, held between the members M², upon upward movement of the plates. The block M⁴ is so positioned between the top and bottom of the members M², that, when the shoulder M³ is in contact therewith, the extreme lower edge of the plate M is flush with the bottom of the unit. The block M⁴ and members M² are here shown as held in position by bolts M⁵ extending through the partitions, the members and the block.

The construction described serves not only as a guide for the plates in their vertical movement, but effectively braces the two side sections of the unit against relative lateral movement. It is a preferred construction, but the details may be variously modified in actual practice.

In practising my method of dredging channels, or removing bars of alluvial deposits, I arrange a plurality of the units alongside of the desired position of the channel to be cut, or upon each side of the bar to be removed. I then arrange a plurality of units in diverging relation, upstream, as clearly shown in Fig. 1 of the drawings. The compartments H and J of the units are then flooded, and the units allowed to rest upon the bottom of the river. In this position the tractive elements sink in the mud, and the bottom of the units also rest upon or in the mud, depending upon the consistency thereof. In any event the tractive elements and the bottom of the units tend to moor the units and hold them in the desired position. I then lower the plates M to the position shown in Figs. 3 and 4, thereby effectually sealing the water against lateral entrance under the units, when the latter are not flat on the bottom of the river.

With the units in the position shown in Fig. 1 the downcoming water is virtually trapped and forced to pass between the units which are arranged in parallelism. Naturally the velocity of this water is greatly increased and the loose mud, sand and other alluvial deposits are carried down the river. There is a considerable lateral pressure of water against each of the units in the dam so formed, but this pressure is effectively resisted by the mooring effect caused by the bottoms of the units and by the tractive elements being buried in the mud, and also very largely, by the fact that the plates M are also deeply embedded in the mud. The plates alone would not be sufficient to resist this pressure. Certainly they would become bent and so strained as to render difficult the subsequent vertical movement within the units. In some cases, if deemed desirable, hawsers might be connected to opposite units to assist in resisting the lateral pres-

sure. The concave and convex formation of the ends of the units permit interfitting engagement, whereby a substantially even surface is presented to the water.

After the channel has been properly cut with the boats positioned as shown in Fig. 1, the sealing plates M are raised and the units are moved up or down the stream. Each unit is self-propelled, and each is provided with tractive elements now embedded in the water. It is not necessary to entirely raise the units, it being sufficient to elevate one end only. One compartment of each unit is therefore emptied, or partially so, by operation of the associated pump, and the unit will then assume the position shown in Fig. 5, the rear tractive elements being in contact with the bottom of the river. These elements are then driven slowly to push the unit along the bottom and when in the desired position, the emptied compartment may again be flooded and the units arranged in the same formation to cut the continuation of the channel.

There is a motor for each tractive element, and it is obvious that the elements on one side of the unit may therefore be operated at a different speed than those on the other side. Consequently it is evident that the units may be guided in the water by merely running the elements at different speeds. Obviously a rudder may be used if desired. By navigating the units as above explained, the dam, made up of a plurality of units, may be moved into another position without materially disturbing the positions of the component units.

The advantages of a self-propelled dam unit are manifest, and especially of a unit which is partially submergible. The units may be moved into and out of position under their own power. Specifically, a dam unit equipped with tractive elements adapted to propel the unit through the water, and also upon the bottom of the river, is especially desirable. The units are usually working in shallow water and when traveling therethrough under power from the tractive elements, if the elements strike the bottom they will crawl thereover until the water beyond is deep enough to again float the unit. If a greater speed is desired in traveling upon the water, a separate propeller may be utilized for this purpose. Any well known form of supplemental propeller is adaptable, so long as it does not project below the bottom of the unit.

The units are of light draft, but are of sufficient height to rest upon the river bottom and still leave above the water a substantial portion of its sides.

It is to be noted that the tractive elements pass over the rollers 6, 6, and that the curvature of the chain is initiated by the foremost of said rollers and ended by the

rearmost. Consequently, no matter which end is elevated, as indicated in Fig. 5 the tractive element is operative either adjacent the bow or stern, to propel the unit 5 while partially submerged.

Many modifications of my invention will be suggested to those skilled in the art, but I do not wish to be limited to the details herein shown, but desire to avail myself of 10 all such embodiments as fall fairly within the scope of the appended claims.

I claim:

1. A floatable dam unit provided with means for varying its displacement, and with 15 self-contained propelling means whereby the unit may be moved through the water or along the bottom thereof.

2. A floatable dam unit as defined provided with means for varying its displacement 20 whereby it may be allowed to rest upon the bottom of the water, and with self-contained means for propelling the unit along the bottom.

3. A floatable dam unit provided with a 25 self-contained powered tractive mechanism capable of propelling the unit through the water or along the bottom, in combination with means for varying the displacement of said unit whereby it may rest upon the bottom, and with means for preventing any lateral flow of water under said unit when resting on the bottom.

4. A river dredging unit comprising a 35 boat of sufficient depth to rest upon the river bottom without submerging its deck, and equipped with pumps and sinking valves for varying its displacement, in combination with means carried by the unit and adjustable to positions below the boat for 40 preventing any lateral flow of water thereunder when it rests upon the river bottom, and means carried by the boat and capable of propelling it through the water or along the bottom, substantially as described.

45 5. A river dredging unit comprising a boat of a depth permitting it to rest upon the river bottom without submerging its deck, in combination with means for varying the displacement of the unit, self-contained 50 means for propelling it through the water or along the bottom thereof, and means carried by the boat for preventing any lateral flow of water thereunder while resting on the bottom.

55 6. A river dredging unit comprising a boat adapted to rest upon the bottom without submerging its deck and equipped with means for varying its displacement, in combination with means for propelling the boat 60 through the water, said means also being operable to propel the boat while it is lightly resting on the bottom, to facilitate the accurate positioning of the boat with respect to the direction of the current flow.

65 7. A river dredging unit comprising a

boat equipped with means for varying its displacement at each end, in combination with means for propelling the boat through the water, said means also being operable to propel the boat on the bottom of the 70 river when either end thereof is not resting upon the bottom, substantially as described.

8. A river dredging unit comprising a boat equipped with means for varying its displacement and with propelling mechanism 75 capable of forcing the boat through the water or along the bottom thereof, said mechanism also serving to moor the unit upon the river bottom, when said unit is sunk to dam forming position.

9. A dam unit equipped with vertically reciprocable elements adapted to control the lateral flow of water beneath the unit and dividing the latter into sections, means forming guideways for said elements and bracing said sections against relative lateral movement, and a member carried by said guideways and limiting the upward movement of said element.

10. A dam unit provided with longitudinally-extending parallel partitions which form, with the top and sides of the unit, water tight compartments on each side thereof, vertically reciprocable elements located wholly below the deck of the unit, extensible below the unit and operable to control the lateral flow of water therebeneath, and members extending between said partitions and securing said sections against relative lateral movement.

11. A dam unit equipped with a plurality of vertically reciprocable aligned plates extensible below the units to control the lateral flow of water therebeneath, said plates having edges adapted for interfitting engagement each to each, whereby a lateral flow of water between the plates is prevented.

12. A dam unit equipped with a vertically reciprocable element extensible below the unit to control the lateral flow of water 110 therebeneath, said element extending longitudinally of the unit and beyond each end thereof.

13. The combination with two dam units arranged in dam forming position, of a vertically reciprocable member carried by each unit and extending beyond the end thereof and adapted for co-operative interfitting engagement with the projecting end of the member carried by the other unit, whereby 115 to control the lateral flow of water between the units, substantially as described.

14. A dam made up of a plurality of units individually movable under their own power through the water or upon the bottom, and carrying means for varying their displacement and additional means for preventing a lateral flow of water therebeneath.

15. The method of dredging a channel in the bottom of a body of running water,

which consists in partially submerging a plurality of dam units until they rest in dam forming position upon the bottom, and thereafter sealing any spaces between the 5 respective units and also between said units and said bottom against lateral flow of the water, whereby the water is forced to cut the desired channel.

16. The method of dredging a channel in 10 the bottom of a body of running water, which consists in moving dam units under their own power to a predetermined position, submerging said units in such position until they rest upon the bottom, and sealing 15 any space between the respective units and also between the units and the bottom of the body of water, against lateral flow of the water under and between said units.

17. The method of dredging a channel in 20 the bottom of a body of running water, which consists in so arranging and partially submerging a plurality of dam units that they rest upon the bottom of the body of water in dam forming position, and thereafter sealing any spaces beneath and between the units and thereby preventing any lateral flow of water beneath said units when so arranged and positioned.

18. The method of cutting a continuous 30 channel in the bottom of a body of running water, which consists in partially submerging a plurality of dam units until they rest in dam forming position upon the bottom whereby the water is forced to cut a section 35 of the desired channel, thereafter decreasing the displacement of the units and moving them to a new position and similar arrangement and causing the water to cut another and continuing section of the 40 channel.

19. The method of cutting a continuous channel in the bottom of a body of running water, which consists in partially submerging a plurality of dam units until they rest 45 in dam forming position upon the bottom whereby the water is forced to cut a section of the desired channel and thereafter moving the units under their own power, and longitudinally of the cut channel, to a simi-

lar dam forming position and forcing the 50 water to cut a continuation of said channel.

20. The method of cutting a continuous channel in the bottom of a body of running water, which consists in partially submerging a plurality of dam units until they rest 55 in dam forming position upon the bottom, thereafter sealing any spaces between the units and the bottom thereby preventing lateral flow of the water under said units, whereby the water is forced to cut a section 60 of the desired channel and thereafter moving the units under their own power and longitudinally of the cut channel, to a similar dam forming position and forcing the water to cut a continuation of said channel. 65

21. The method of cutting a continuous channel in the bottom of a body of running water, which consists in partially submerging a plurality of dam units until they rest 70 in dam forming position upon the bottom, thereafter sealing any spaces between the units and the bottom, thereby preventing lateral flow of the water under said units, whereby the water is forced to cut a section 75 of the desired channel, thereafter decreasing the displacement of the units and moving them to a new position and similar arrangement and causing the water to cut another and continuing section of the channel.

22. The method of cutting a continuous 80 channel in a body of running water which consists in arranging, under their own power, a plurality of dam units in dam forming position, submerging said units in such arrangement until they rest upon the bottom of the river, thereafter sealing the spaces between said units and between the units and the river bottom, whereby the water is forced to cut a section of the desired 85 channel, and thereafter moving the units 90 along the bottom of the river while preserving the dam forming arrangement, again sealing the spaces as before said and forcing the water to cut a continuation of the channel, substantially as described. 95

In testimony whereof I affix my signature.

CARL J. BAER.
